(57) **CLAIM**

I claim the ornamental design for a fluid dispenser, as shown and described.

DESCRIPTION

FIG. 1 is a perspective view of a fluid dispenser.

FIG. 2 is a front view of the fluid dispenser of FIG. 1.

FIG. 3 is a right-side view of the fluid dispenser of FIG. 1.

FIG. 4 is a rear view of the fluid dispenser of FIG. 1.

FIG. 5 is a left-side view of the fluid dispenser of FIG. 1.

FIG. 6 is a top plan view of the fluid dispenser of FIG. 1; and,

FIG. 7 is a bottom plan view of the fluid dispenser of FIG. 1.

The broken lines in the Figures are for the purpose of illustration and form no part of the claimed design.
